FIG. 6 is a bottom view thereof;

FIG. 7 is a left side view thereof;

FIG. 8 is a right side view thereof;

FIG. 9 is a front perspective view of a pillows cushion and frame module assembly for patient interface showing a second embodiment of our new design;

FIG. 10 is a front view thereof;
 FIG. 11 is a rear view thereof;
 FIG. 12 is a top view thereof;
 FIG. 13 is a bottom view thereof;
 FIG. 14 is a left side view thereof;
 FIG. 15 is a right side view thereof;
 FIG. 16 is a front perspective view of a pillows cushion and frame module assembly for patient interface showing a third embodiment of our new design;
 FIG. 17 is a front view thereof;
 FIG. 18 is a rear view thereof;
 FIG. 19 is a top view thereof;
 FIG. 20 is a bottom view thereof;
 FIG. 21 is a left side view thereof;
 FIG. 22 is a right side view thereof;
 FIG. 23 is a front perspective view of a pillows cushion and frame module assembly for patient interface showing a fourth embodiment of our new design;
 FIG. 24 is a front view thereof;
 FIG. 25 is a rear view thereof;
 FIG. 26 is a top view thereof;
 FIG. 27 is a bottom view thereof;
 FIG. 28 is a left side view thereof;
 FIG. 29 is a right side view thereof;
 FIG. 30 is a front perspective view of a pillows cushion and frame module assembly for patient interface showing a fifth embodiment of our new design;
 FIG. 31 is an enlarged perspective view of the pillows cushion and frame module shown in isolation;
 FIG. 32 is a front view thereof;
 FIG. 33 is a rear view thereof;
 FIG. 34 is a top view thereof;
 FIG. 35 is a bottom view thereof;
 FIG. 36 is a left side view thereof;
 FIG. 37 is a right side view thereof;
 FIG. 38 is a front perspective view of a pillows cushion and frame module assembly for patient interface showing a sixth embodiment of our new design;
 FIG. 39 is a front view thereof;
 FIG. 40 is a rear view thereof;
 FIG. 41 is a top view thereof;
 FIG. 42 is a bottom view thereof;
 FIG. 43 is a left side view thereof;
 FIG. 44 is a right side view thereof;
 FIG. 45 is a front perspective view of a pillows cushion and frame module assembly for patient interface showing a seventh embodiment of our new design;
 FIG. 46 is a front view thereof;
 FIG. 47 is a rear view thereof;
 FIG. 48 is a top view thereof;
 FIG. 49 is a bottom view thereof;
 FIG. 50 is a left side view thereof;
 FIG. 51 is a right side view thereof;
